UNITED STATES PATENT OFFICE

JOSIAH BRADLEY, OF BROOKLYN, NEW YORK

RETORT-OPERATING APPARATUS

Application filed August 22, 1924. Serial No. 733,456.

My present invention relates to an apparatus for extracting the volatiles from coals, lignites and similar materials for the production of gas, oil and like products, and more particularly to that form of such apparatus in which the temperature is maintained at a sufficiently low heat to extract the volatiles without appreciable chemical action and in which the necessary heat for carrying on the process is furnished by the burning of the charge at the lower end thereof, although with some forms of materials it may be necessary to supply the necessary heat from other sources. The present invention more especially relates to apparatus for automatically slicing the grate bar, that is removing at certain intervals a certain amount of the burning charge at the lower end of the retort, and the invention furthermore includes devices for delivering the charge as extracted from the retort, the operation of the latter devices being dependent upon the operation of the former. The operation of these devices is furthermore preferably dependent upon the temperature of the retort, although as will be understood other means of automatic operation may be employed.

One form of apparatus which may be used in carrying out my present invention will be hereinafter more particularly described in conjunction with the accompanying drawings in which,—

Fig. 1 is an elevation and partial section illustrating the temperature control devices for opening and closing a switch to a motor for operating the slicer bar.

Fig. 2 is a sectional elevation on line 2—2, Fig. 1.

Fig. 3 is a diagrammatic plan of the parts employed for operating the apparatus in carrying out the invention, and

Fig. 4 is a diagrammatic elevation showing a retort and the relative positions of the parts to which my present invention relates.

Referring to the drawing I have diagrammatically illustrated a retort at 10. This retort may be of any suitable structure. At its upper end the retort is preferably provided with a feed drum 11 which may be operated automatically or otherwise, depending upon

the pressure or temperature within the retort so as to feed the coal or other material to the retort in such a manner as to keep the same substantially filled at all times during its operation. At the lower end of the retort the same is provided with a slicer bar 12 which preferably swings over the grate of the retort in order to remove a predetermined portion of the charge at the lower end thereof. Beneath the slicer bar the apparatus also includes a discharge drum 13 into which the discharged portions of the charge from the retort are caused to pass in order to be delivered from the hopper in which they are originally received to any suitable receptacle or other device, such for example as a car or truck by which the residue from the retort may be removed.

The slicer bar 12 is mounted to swing on a pivot indicated at 12' and is actuated by a rocker arm 14 pivotally mounted at 15 and connected at one end by a link 16 to the slicer bar. At its opposite end the rocker arm 14 is provided with a rack 17 meshing with a worm 18 which is carried by a shaft 19. It will be understood that the shaft 19 is suitably journaled, and by a coupling 20 provided at one end thereof this shaft 19 is connected to a shaft 21 also suitably journaled and having a worm gear 22 mounted thereon. This worm gear 22 meshes with a worm 23 fitted on the shaft of a motor 24 employed, as hereinafter described, to swing the rocker shaft 14 by means of the worms, worm gears and shafts as just described to operate the slicer bar 12.

I also employ a suitable motor 25 for operating the discharge drum 13. The shaft 26 of this motor 25 is connected to a shaft 27 by a coupling 28. On the shaft 27 there is a worm 29 meshing with a worm gear 30 on the shaft of the discharge drum by which devices, as will be understood, when the motor is operated, the discharge drum will be turned.

Associated with the retort 10 and connected in a suitable position to the wall thereof there is a casing 31. This casing is provided with a cover 32 and fitted with a face 33 made of glass or other transparent material.

The casing contains devices for opening and closing a switch in the circuit to the motor for operating the slicer bar. The operation of the switch is preferably dependent upon the temperature in the retort. Devices are also employed for controlling the opening and closing of the circuit to the motor for operating the discharge drum. The devices in the casing include an electro-magnet 34 secured in position within the casing on a bracket 35 and having its armature 36 pivotally connected to a lever 37. The lever 37 is pivotally connected in the casing as indicated at 38. One end of the lever 37 is connected to the armature 36 as hereinbefore stated and at its opposite end the lever 37 is provided with a roller 39. The normal position of the lever 37 and the magnet armature 36 is determined by a stop 40 and a spring 41, the lower edge 20 of the lever being adapted to contact with the stop and the spring extending between the lever and a hook provided thereon on the frame holding the winding of the magnet. This normal position of the armature and lever is that shown in full lines in Fig. 1 in which the armature is separated from the core of the magnet. The casing 31 in suitable positions is provided with binding post terminals 42, 43 which by lead wires 44 and 45 respectively are connected to the terminals of the magnet.

The casing 31 also contains a suitable switch which is preferably a liquid contact switch. This switch includes a receptacle or reservoir 46 having a suitable base resting upon and secured to a bracket 47 by which the switch is maintained in position in the casing. The receptacle 46 contains a quantity of liquid mercury 48 above which there may be a covering of oil or other suitable material. One of the terminals of the switch is indicated at 49. This extends sufficiently far into the receptacle to enter the mercury bath and is also connected to a terminal or binding post 50 insulated from the casing by a washer 51 of rubber or asbestos or other similar material. The binding post 50 is connected by a lead wire 52 to a binding post terminal 53 suitably secured in the casing 31. The other terminal of the switch comprises a switch arm 54 adapted to be raised and lowered out of and into the mercury bath contact. As will be understood one end of the switch arm is lowered into and raised out of the mercury bath to close an electric circuit and for this purpose this end of the switch arm may be provided with a contact member 55. The opposite end of the switch arm 54 is pivotally connected to one end of a lever 56 as indicated at 57. This lever 56 is pivotally mounted at its opposite end in the casing as indicated at 58. The lever 56 at one side thereof preferably the lower side when the parts are in their operative positions is provided with a notch indicated at 59, the pur-

pose and function of which will be herein-after described.

When the electro-magnet 34 is energized as hereinafter described the lever 37 is actuated to bring the roller 39 to bear against the underedge of the lever 56 in order to return and normally maintain the same and the switch arm 54 in their initial positions until the circuit through the electro-magnet is broken, permitting the same to become deenergized.

Associated with the lever 56 there is a bell crank lever 60. This bell crank lever 60 is pivotally mounted on a suitable support in the casing as indicated at 61. One arm of the bell crank lever as indicated at 62 is provided at its extremity with a trip or finger 63 which is pivotally connected to the arm 62 as indicated at 64 and is normally maintained in an initial position against a stop 65 by means of a spring 66 or otherwise. The other arm 67 of this bell crank lever 60 is provided with a slot 68. Extending into or through the slot 68 is the extremity of an arm 69. This arm 69 is integral with or carried by a lever 70 which at one end is pivotally mounted at 71 between suitable lugs 72 secured in a centrally disposed position to the outer face of a diaphragm 73. The lever 70 is pivotally mounted as indicated at 74 between lugs 75 suitably secured to the base of the casing. The end of the lever adjacent the arm 69 extends appreciably beyond the pivotal point 74 as indicated at 76 and the lever and the parts associated therewith are normally maintained in position by means of a spring 77 pressing against the end 76 of the lever. The diaphragm 73 may be made of any suitable metal or other material having a relatively high coefficient of expansion and lies within a recess in the base 78 of the casing, while the lugs 72 extend through an opening 79 in this base so that the lever 70 and associated parts lie within the casing exteriorly of the base.

It will be understood that the lever 56 is grounded in the base 78 and that in a suitable position the base 78 is provided with a terminal 80 connected by a lead wire 81 with an exterior binding post terminal 82 forming the other terminal of the switch maintained within the casing.

Associated with the parts hereinbefore described and employed in the automatic operation of the same I provide a starting rheostat 83 for the circuit of the slicer bar motor 24. The positive terminal of this starting rheostat is connected by a lead 84 to the binding post terminal 53. In this circuit there is a battery or other source of energy 84'. The binding post terminal 82 is connected by a lead 85 to one positive terminal 86 of one field winding of the slicer bar motor and also to another positive terminal 87 of a second field winding of the slicer bar motor by a lead 88. The negative terminal of the first field wind-

ing is connected by a lead 89 to a switch clip 90. The negative terminal 91 of the other field winding of the slicer bar motor is connected by a lead 92 to a switch clip 93. I employ a switch lever 94 pivotally mounted at 95 and adapted to bear against either the switch clip 90 or the switch clip 93. The pivotal point 95 of the switch lever 94 is connected by a lead wire 96 to the negative terminal of the starting box 83.

10 The lead 85 is common to two sets of reversely wound fields in the slicer bar motor 24. When the circuit is closed at the switch clip 90 the current passes through one of these fields and the motor is turned in one direction whereas when the circuit is closed at the switch clip 93 the current flows through the other field and the motor is turned in the opposite direction, it being understood that these reversely wound motor fields have separate and independent return leads 89 and 92, the former going to the switch clip 90 and the latter to the switch clip 93.

Associated with the lever 94 is a segment rack 97 adapted to mesh with a gear 98. I also employ a lever 99 pivotally mounted at 100 and at one end provided with a segment rack 101 also meshing with the gear 98, while the opposite end 102 of the lever 99 is pivotally connected by a rod 103 to one end of a rocker lever 104 pivotally mounted at 105. The operating mechanism also includes a reciprocating bar 106. In a suitable position this bar is provided with a slot 107 through which extends a pin 108 carried by the opposite end of the rocker lever 104. One end of the reciprocating bar 106 is provided with a slot 109 and in a suitable position the slicer bar 12 is provided with a pin 110 which engages in this slot 109. Adjacent the other end of the reciprocating bar 106 the same is provided with a projection 111, the oppositely disposed surfaces of which are inclined planes. I also employ a rider member 112 fitted with a roller or similar device 113 adapted to contact with the oppositely disposed inclined planes of the projection 111. This rider 112 is mounted on a spindle 114 operating in a casing or bearing 115 and normally maintained in position by a spring 116. It will be understood, of course, that suitable devices may be employed for regulating the tension of the spring and the resultant pressure with which the roller bears against the inclined planes of the projection 111.

55 I furthermore employ a rocker lever 117 pivotally mounted at 118. This rocker lever 117 is adapted to cooperate with a switch lever 119 pivotally mounted at 120 so as to actuate the same, moving the switch lever into and out of contact with a terminal 121. Associated with the rocker lever 117 there is a reciprocating rod 122. This may be mounted so as to slide in guides 123. At one end the 60 rod 122 is pivotally connected to a lever 124

pivotaly mounted at 125. This lever 124 is provided with an arm 126 normally bearing at its extremity against the surface of a disk 127 mounted on the shaft of the discharge drum 13 and fitted with a cam 128 cooperating with the end of the arm 126 to throw the lever 124 which is normally maintained in that position in which the arm 126 contacts with the disk 127 by a spring 129 or otherwise. Also associated with the rocker lever 117 is a bell crank lever 130 pivotally mounted at 131. One arm 132 of this bell crank lever is adapted to contact with a projection 133 on the side of the rocker lever 117 which furthermore is provided with a corresponding but oppositely disposed projection 134 which is adapted to strike against the end of the rod 122. The other arm 135 of the bell crank lever 130 is provided with a projection 136, the surfaces of which are oppositely disposed inclined planes. The lever 130 is maintained in an initial position against a stop 137 by means of a spring 138 or otherwise. Associated with the bell crank lever 130 is a lever 139 which is pivotally mounted at 140. At one end the lever 139 carries a roller 141 adapted to bear against the inclined planes of the projection 136. At its opposite end the lever 139 is provided with a segmental rack 142 meshing with the teeth of the gear 98.

95 I also employ a starting box or rheostat 143 for the circuit of the motor 25 for operating the discharge drum 13. The positive terminal of this rheostat 143 is connected by a lead 144 to the positive terminal of the motor 25. 100 In this circuit there is a battery or other source of power 144'. The negative terminal of the motor 25 is connected by a lead 145 to the contact 121. In this motor circuit there is a shunt circuit consisting of a lead 146 extending from a tapped point 147 in the lead 144 to the binding post terminal 42 of the electro-magnet 34 and a lead 148 extending from a tapped contact point 149 in the lead 145 to the binding post terminal 43. The lever 119 is connected to the negative terminal of the starting rheostat 143 by a lead 150.

105 In the use of the apparatus as hereinbefore described the material to be treated is supplied to the retort through the feed drum 11 which may be operated in any desired manner so as to maintain the retort in a condition in which it is substantially filled with the material. The heat necessary for the extraction of the volatiles from the material is preferably generated by burning the charge at the lower portion thereof immediately above the grate bar. This, as will be understood, creates a predetermined temperature in the retort and this temperature reacts upon and determines the condition and position of the diaphragm 73 which controls the closing of the circuit to the slicer bar motor. Consequently the control as shown and described is a thermostatic one. Obviously, however, 110 115 120 125 130

this control might be effected by means of a pressure within the retort or otherwise. As thermostatically controlled the parts of the apparatus are in the positions as shown in full lines, Fig. 1, of the drawings when the slicer bar is stationary. Now assuming that the temperature of the charge has risen to a predetermined point sufficiently high to expand the diaphragm 73, that is to cause the 5 same to move outwardly, it will be apparent that this movement of the diaphragm swings the lever 70 in a counter clockwise direction thereby raising the free end of the arm 69 which extends through the slot 68 in the bell crank lever 60. In their normal positions the end of the finger 63 is in contact with the adjacent lower edge of the lever 56. The swinging of the lever 70 and the movement of its arm 69, as hereinbefore described, causes the bell crank lever 60 to swing in a clockwise direction wherein the end of the finger 63 rides off the notched lower edge of the lever 56 thereby permitting the lever to drop and the switch arm to move likewise 10 causing the contact member 55 to enter the mercury bath and close the circuit to the motor for operating the slicer bar, as shown in dotted lines, Figure 1. This circuit is therefore closed from the positive terminal 15 of the starting rheostat 83, through the lead wire 84 to the binding post 53, through the switch and the frame of the casing to the binding terminal 82, through the lead wire 85 to the terminal of one of the field windings 20 of the motor 24, through this field winding to the other terminal thereof, through the lead wire 89 to the switch clip 90, through the switch lever 94, through the lead wire 96 to the negative terminal of the starting rheostat. 25 This connection therefore operates the motor in the direction necessary to swing the rocker arm 14 in a clockwise direction so that through the link 16 the slicer bar is moved from left to right as shown in Fig. 3 of the drawing. After the slicer bar has moved a predetermined distance the pin 110 carried thereby abuts against the right hand end of the slot 109. The continued movement of the slicer bar in this direction carries with it 30 the reciprocating bar 106. This movement of the reciprocating bar causes the roller to ride on the left hand inclined plane on the projection 111 until the roller reaches the apex of the planes, traveling of course under the action of the spring 116. When the roller reaches the apex of the planes or substantially so the left hand end of the slot 107 comes into contact with the pivotal point or pin 108 whereby as soon as the roller crosses the apex 35 line of the inclined planes the spring automatically causes the same to descend the left hand plane imparting a quick movement to the reciprocating bar which through the bar is also imparted to the rocker lever 104 and 40 by the same to the connecting rod 103 to

swing the lever 99 in a clockwise direction. This movement of the lever 99 imparts a partial rotation to the gear 98 by means of the segmental rack 101 and the rotation of the gear causes the lever 94 to swing in a clockwise direction through the action of the segmental rack 97 causing the lever to break its connection with the contact 90 and eventually to bear against the contact 93. 45

During this operation the rocker lever 117 and the switch lever 119 are in the positions, as shown in Fig. 3. The operation of the gear 98 also causes a clockwise movement of the lever 139 by means of the segmental rack 142 and this movement of the lever 139 brings the roller 141 into contact with the adjacent inclined plane on the arm of the bell crank lever 130 swinging the lever in a counter clockwise direction against the action of the spring 138 and bringing the end of the arm 132 into contact with the projection 133 which swings the lever 117 causing the same to move the switch lever 119 into contact with the contact or terminal 121. This movement of these parts completes the circuit through the starting rheostat 143 to the motor 25 by the lead 144, then by way of the lead wire 145 from the negative terminal of the motor 25 to the terminal contact 121 through the switch lever 119 and through the lead wire 150 to the negative terminal of the starting rheostat 143. Simultaneously the shunt circuit to the electro-magnet 34 is also closed through the lead wire 144 from the positive terminal of the starting rheostat 143 to the lead wire 146 to the binding post terminal 42, thence through the electro-magnet to the binding post terminal 43, through the lead wire 148 to the lead wire 145, through the terminal 121, the lever 119, and thence through the lead wire 150 to the negative terminal of the starting rheostat 143. The circuit to the motor 25 being thus closed the motor will operate the worm gear 30 on the shaft of the discharge drum 13 causing the latter to complete a revolution when the cam 128 will trip the lever 124 by acting against the arm 126 and in so doing, as will be understood, the bar 122 is moved from its initial position and in so doing it in turn 55 swings the rocker lever 117 to its initial position thereby opening the circuit to the magnet 34 at the terminal contact 121 and also opening the circuit to the motor 25 at the same place. It will now be understood that when the circuit to the magnet 34 is closed the armature thereof is attracted to the core and this in turn swings the lever 37 so as to raise the lever 56 and lift the contact arm 54 so that the contact member 55 is removed from the mercury bath thereby furthermore breaking the slicer bar motor circuit at the switch in the casing. It will also be understood that as long as the circuit to the electro-magnet is closed the switch lever 56 will be 60 raised to keep the circuit open at the switch. 130

After the slicer bar has thus been actuated to remove a predetermined portion of the charge above the grate bar of the retort the temperature will be lowered materially, permitting the diaphragm 73 to contract and causing the lever 74 to swing in a clockwise direction which lowers the free end of the arm 69 by which movement the bell crank lever 60 is swung in a counter clockwise direction. The purpose of employing the pivoted finger 63 is to permit this turning movement of the bell crank lever to its initial position, if necessary, before the lever 56 is raised so as not to interfere in any manner with the operation of the switch. Of course after the lever 60 has returned to its normally initial position the opening of the switch in the casing at the completion of the movement of the slicer bar permits the pivoted finger 63 to assume its normal position and after the circuit to the electro-magnet 34 is broken the switch lever 56 will be permitted to rest upon the end of the finger 63 to maintain the switch arm in the position in which the switch is open.

Obviously the parts are now set for the operation of the slicer bar in the opposite direction and the operation of the motor 25 to cause the discharge drum to turn another revolution. It will be noted, however, that the parts are so timed that in the operation thereof the switch lever 94 is not moved sufficiently far to bear against the switch clip 93 until after the switch lever 119 has been brought into contact with the terminal contact 121 so that the switch in the casing is open before it is possible to close the circuit again at both the switch and through the switch lever 94 and its switch clip 93. The parts being thus reset when the temperature again rises to a point where the diaphragm expands sufficiently to trip the bell crank lever 60 the circuit will be closed again through the switch in the casing by the fall of the lever 56 which permits the contact piece 55 to enter the mercury bath.

With the circuits thus closed the motor 24 is turned in the opposite direction, the circuits being the same as those hereinbefore described with the exceptions of the current passing to the other field or set of fields of the motor 24 which, as will be understood, are wound in a direction opposite to that of the first named field or fields of the motor, and through the switch clip 93 and the switch lever 94 instead of through the switch clip 90 and the switch lever 94. The movement of the slicer bar will then be in the opposite direction and the movement of the reciprocating bar 106 will also be in the opposite direction and this movement of the reciprocating lever in the opposite direction by the parts associated therewith will swing the lever 99 in the direction opposite to that in which it was originally moved reversing the direction in which the gear 98 was originally turned and therefore reversing the direction in which the parts operated by the gear were originally turned. It will be understood that the operation of the other parts including the closing of the circuits to the electro-magnet 34 and the motor 25 are in all respects similar to those hereinbefore described in connection with the first operation of these parts.

It will furthermore be understood that the apparatus hereinbefore described is merely illustrative of a set of devices which may be employed in carrying out my invention for the automatic operation of a slicer bar of a retort for extracting the volatiles from coals, shales, lignites and the like, and for automatically and simultaneously operating a discharge drum for such an apparatus and that other similar and equivalent devices may be employed for this purpose without departing from the nature and spirit of my invention.

I claim as my invention:

1. In an apparatus of the class described, a slicer bar, a motor for actuating the same, a discharge drum, a motor for operating the discharge drum, means actuated automatically for opening and closing a circuit to the motor for actuating the slicer bar, and means for automatically opening and closing a circuit to the motor for actuating the discharge drum to operate the discharge drum each time the slicer bar is actuated.
2. In an apparatus of the class described, a slicer bar, a motor for actuating the slicer bar, a discharge drum, a motor for actuating the discharge drum, devices operated thermostatically for opening and closing a circuit to the slicer bar motor to move the slicer bar predetermined distances forward and backward, and devices actuated automatically for opening and closing a circuit to the discharge drum motor each time the slicer bar is operated.
3. In an apparatus of the class described, a slicer bar, a motor for actuating the slicer bar, a discharge drum, a motor for actuating the discharge drum, a switch, means for automatically closing the said switch at intervals to close a circuit to the slicer bar motor for operating the slicer bar, and means operative automatically after the slicer bar has moved a predetermined distance for opening the said switch and simultaneously closing a circuit to the said discharge drum motor.
4. In an apparatus of the class described, a slicer bar, a motor for actuating the slicer bar, a discharge drum, a motor for operating the discharge drum, a switch, automatic means for closing the said switch at intervals to close a circuit to the slicer bar motor for operating the same, means operative automatically after the said slicer bar has traveled a predetermined distance for opening the said switch and for simultaneously closing a circuit to the said discharge drum mo-

tor, and means operative after the discharge drum is turned a complete revolution for automatically opening the circuit to the discharge drum motor.

5. In an apparatus of the class described, a slicer bar, a motor for actuating the slicer bar, a discharge drum, a motor for actuating the discharge drum, a switch, a thermostatic device for closing said switch to close a circuit to the said slicer bar motor, means operative after the slicer bar has been moved a predetermined distance for automatically opening the circuit at the said switch and also opening and closing the motor circuit at other points whereby when the switch is closed a second time the motor is driven in the opposite direction to return the slicer bar to its initial position, means automatically operated when the slicer bar has been moved a predetermined distance for closing a circuit to the discharge drum motor, and means operative when the discharge drum has turned a complete revolution for automatically opening the circuit to the said discharge drum motor.
25. 6. In an apparatus of the class described, a slicer bar, devices for intermittently operating the slicer bar, a discharge drum, devices for turning the discharge drum, and means for automatically actuating the devices for turning the discharge drum after each operation of the slicer bar.

Signed by me this 6th day of August, 1924.

JOSIAH BRADLEY.
